UNITED STATES PATENT OFFICE.

GEORGE J. BEAUDET, OF PROVIDENCE, RHODE ISLAND.

COMBINED STOVE-LID AND POT LIFTER.

1,360,359.

Specification of Letters Patent. Patented Nov. 30, 1920.

Application filed January 12, 1920. Serial No. 350,810.

To all whom it may concern:

Be it known that I, GEORGE J. BEAUDET, a citizen of the United States, residing at Providence, in the county of Providence and State of Rhode Island, have invented certain new and useful Improvements in a Combined Stove-Lid and Pot Lifter, of which the following is a specification.

This invention relates to stove lid and pot lifters, and the primary object of the invention is to provide an improved stove lid lifter which is so constructed that stove lids can be readily and quickly lifted without strain upon the operator's wrist or without 10 the likelihood of the lid becoming disconnected from the lifter.

Another object of the invention is to provide an improved stove lid lifter embodying an annularly extending handle which is disposed over the stove lid engaging foot, so that the hand of the operator will be adjacent to the center of the lid so as to reduce 20 the strain upon the wrist of the user.

A further object of the invention is the provision of an improved stove lid lifter embodying a handle positioned above the foot for engaging the stove lid having a hook arranged in the shank thereof intermediate the handle and foot for engaging the stove 30 lid for engaging the pot or the like for permitting the easy handling thereof.

A further object of the invention is the provision of a stove lid lifter having an angularly disposed handle positioned above the 35 foot for engaging the stove lid, which is so constructed as to provide a rest for the thumb of the operator, thereby permitting a firm grip to be obtained upon the handle.

A still further object of the invention is the provision of an improved stove lid and 40 pot lifter of the above character which is durable and efficient in use, one that is simple and easy to manufacture, and one which can be placed upon the market at a reasonable cost.

Other objects of the invention will appear in the following detailed description taken in connection with the drawing, in which drawing:

50 Figure 1 is a perspective view of the improved stove lid and pot lifter showing the same in operation.

Fig. 2 is a fragmentary elevation of the handle for the lifter.

55 Referring to the drawings, in detail,

wherein similar reference characters designate corresponding parts throughout the several views, the numeral 5 indicates the improved stove lid lifter, which includes the inclined shank 6 having its lower end bent outwardly and downwardly as at 7 and provided with a curved forwardly projecting lid engaging foot 8. The downwardly and forwardly projecting portion 7 of the inclined shank 6 directly in rear of the foot 65 8 is provided with oppositely extending outwardly projecting ears 9 formed on the edges of the shank 6 for engaging the upper surface of a stove lid 10. The stove lid 10, which is shown merely to illustrate the use 70 of the lifter, is of the ordinary or any preferred construction and includes the usual recess 11 for the foot 8 of the stove lid lifter and the inwardly extending ears 12 formed on the opposite side walls of the recess. 75 The upper end of the shank is provided with a substantially right angularly disposed handle portion 12, which terminates approximately above the foot 8. The handle portion 12 as shown is reduced to form a polygonal bar 13, to which is secured the hand grip 14 which includes a wire 15 wound spirally around the bar 13. As clearly 80 shown the convolutions of the wire 15 gradually increase in diameter toward the outer 85 end of the handle as at 16 until a certain point is reached when the convolutions gradually decrease in diameter. The outer end of the wire 15 is secured to the outer end of the bar 13 and is bent to provide an eye 90 17, which projects outwardly of the bar 13 and lies in the same plane therewith. The eye 17 is formed relatively large and forms a thumb rest for the hand of the operator when a stove lid or pot is being lifted. The 95 eye 17 also forms a convenient means for hanging the lifter up when not in use.

The shank 6 adjacent to the forwardly and downwardly projecting portion 7 is provided with a hook 18, which is riveted 100 or otherwise secured to the shank as at 19. The hook forms means for engaging the bails of pots to permit the convenient lifting and handling thereof.

From the foregoing description it can be 105 seen that an improved stove lid and pot lifter has been provided of exceptionally simple and durable construction, which permits the easy and convenient lifting of stove lids or pots without strain upon the wrist 110

of the operator and which will permit a firm grip to be obtained upon the handle portion thereof.

Changes in details may be made without departing from the spirit or scope of my invention; but,

I claim:

1. A lifter comprising an inclined shank, a forwardly projecting handle formed on the shank and extending at an angle thereto, a hand grip formed on the angle portion, and a forwardly projecting thumb piece formed on the hand grip and extending in the same plane therewith.
2. A lifter comprising an inclined shank, a forwardly projecting handle arranged at substantially right angles to the inclined shank, a hand grip arranged on the handle, and a thumb receiving eye formed on the

hand grip and arranged in the same plane 20 therewith.

3. A lifter comprising an inclined shank, a downwardly and forwardly projecting portion formed on one end of the shank, a forwardly projecting foot formed on the downwardly and forwardly projecting portion, outwardly extending ears formed on the foot, a downwardly projecting handle formed on the upper terminal of the inclined shank and extending at substantially 30 right angles thereto, a spirally wound hand grip arranged on the handle, the forward end of the hand grip being curved to provide an eye, the said eye extending in the same plane with the handle and arranged 35 above the foot.

GEORGE J. BEAUDET.
